[57] CLAIM

The ornamental design for a display carton, as shown and described.

DESCRIPTION

FIG. 1 is a perspective view of a display carton showing my new design;

FIG. 2 is a top plan view thereof;

FIG. 3 is a rear side elevation thereof;

FIG. 4 is a right side elevation thereof;

FIG. 5 is a front elevation thereof;

FIG. 6 is a left side elevation thereof; and

FIG. 7 is a bottom plan view thereof.

The broken lines showing of product in FIG. 1 is for illustrative purposes only and forms no part of the claimed design.

FIG. 1

FIG. 2

FIG. 3

FIG. 4
